[57] **CLAIM**

The ornamental design for a rounded chimney cap, as shown and described.

DESCRIPTION

FIG. 1 is a perspective view of my new design of a rounded chimney cap;

FIG. 2 is a top view of the rounded chimney cap of FIG. 1; FIG. 3 is a front view of the rounded chimney cap shown in FIG. 1, the rear, left and right sides being identical thereto; and,

FIG. 4 is a bottom view of the rounded chimney cap of FIG. 1.

The broken-line showing of environmental structure in FIG. 1 is for illustrative purposes only and forms no part of the claimed design.
